PAPER CARTON CUTTER

Harry Hanson, Menomonie, Wis.

Application February 6, 1941, Serial No. 377,723

4 Claims. (Cl. 30—2)

This invention relates to a paper carton cutter, and has for the primary object the provision of a tool of the above stated character which will permit a person to easily and quickly cut any wall of a paper carton for the purpose of opening the latter and with a maximum amount of safety both to the person and to the contents of the carton.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation partly in section showing a cutter associated with a wall of a carton for the purpose of severing said wall and constructed in accordance with my invention.

Figure 2 is a side elevation showing the cutter adjusted for cutting a wall of a carton adjacent to one edge thereof.

Figure 3 is a top plan view, partly in section, illustrating the device.

Figure 4 is a sectional view illustrating the cutting means.

Figure 5 is a fragmentary side elevation showing a knife carrying plate.

Figure 6 is a perspective view illustrating a gauge element.

Figure 7 is a plan view illustrating the cutting blade.

Referring in detail to the drawings, the numeral 5 indicates the main plate of the device which acts as a runner and has its forward end bent backwardly upon itself and rolled to form a handle 6. The handle inclines upwardly and rearwardly over the main plate.

Fixed on the plate 5 at the trailing edge thereof and arranged at right angles to said plate is a knife carrying plate 7 provided with an arcuate slot 8 to receive set screws 9 and 10.

Any type of flat blade may be used as a knife such as a razor blade indicated by the character 11. The blade 11 is fastened onto the plate 7 by the set screw 9 and also by a set screw 12. The set screw 12 extends through an aperture 13 in the plate and which is located adjacent the lower edge of the plate so as to position the blade 11 as to bring one of its cutting edges to extend in a plane below the lower edge of the plate 7 for cutting through a wall of a carton 14. By adjusting the set screw 9 in the slot 8 the cutting

edge of the blade may be brought closer or moved further from the wall of the carton, or in other words to vary the distance of the cutting edge of the blade that may act in severing the wall of the carton.

An L-shaped gauge element 15 is supported on the plate 7 by the set screws 10 and 12 and is spaced from the blade 11 by a washer 16 arranged on the set screw 12. It is preferable that this washer be of the spring type to permit the gauge element 15 to yield relative to the blade. The corner A of the gauge element is adapted to ride the wall of the carton being severed for the purpose of regulating the depth of the cut made in the carton and consequently permit adjustment of the device so that the carton wall can be cut without danger of severing or cutting the contents of the carton.

By moving the set screw 10 along the slot 8 the corner A of the gauge element may be adjusted relative to the wall of the carton. The gauge element further acts as a guard or protector against persons cutting a finger or the like while using this device.

A guard element 16 in the form of an elongated plate provided with a slot 17 extending endwise thereof is associated with the device for the purpose of guiding the movement of the tool along a wall of a carton while the adjoining wall is severed by the blade. The guard element receives the set screws 10 and 12 through the slot 17 thereof and provides means whereby the guard element may be adjusted into and out of operative position.

As shown in Figure 1, the guard element is in an inoperative position and as shown in Figure 2 the guard element is brought into operative position.

It is also preferable that a washer or spacer 18 be arranged on the set screw 12 between the gauge element and the guard element. Further, it is to be noted that the set screws are equipped with wing nuts 19 whereby said set screws may be readily adjusted along the slot 8 and secured in any of their adjusted positions.

While I have shown and described the preferred embodiment of my invention, it will be understood that minor changes in construction, combination and arrangement of parts may be made without departing from the spirit and scope of the invention as claimed.

Having thus described the invention, what I claim is:

1. In a carton cutting tool, a combined handle and runner, a cutting blade carrying means se-

cured to said combined handle and runner, a blade adjustably mounted on said means, a gauge element adjustably mounted on said means and associated with the blade for regulating the depth of cut that may be made by said blade, and a guard element adjustably mounted on said means and having operative and inoperative positions.

2. In a carton cutting tool, a runner plate, a handle at one end of said plate, a cutting blade carrying plate secured to the other end of the runner plate and arranged at right angles thereto and having an arcuately curved slot, set screws mounted for movement in said slot, a set screw carried by said cutting blade carrying plate adjacent its lower edge, a blade having a slot receiving one of the first-named set screws and the second-named set screw.

3. In a carton cutting tool, a runner plate, a handle at one end of said plate, a cutting blade carrying plate secured to the other end of the runner plate and arranged at right angles thereto and having an arcuately curved slot, set screws mounted for movement in said slot, a set screw

carried by said cutting blade carrying plate adjacent its lower edge, a blade having a slot receiving one of the first-named set screws and the second-named set screw, and an L-shaped gauge element having apertures to receive one of the first-named set screws and the second-named set screw.

4. In a carton cutting tool, a runner plate, a handle at one end of said plate, a cutting blade carrying plate secured to the other end of the runner plate and arranged at right angles thereto and having an arcuately curved slot, set screws mounted for movement in said slot, a set screw carried by said cutting blade carrying plate adjacent its lower edge, a blade having a slot receiving one of the first-named set screws and the second-named set screw, and an L-shaped gauge element having apertures to receive one of the first-named set screws and the second-named set screw, and a guard element including an elongated plate having a slot to receive the last-named set screw.

HARRY HANSON.
